(57) **CLAIM**

The ornamental design for the mower blade, as shown and described.

DESCRIPTION

FIG. 1 is a perspective view of a mower blade of the present invention;

FIG. 2 is a front view of the mower blade;

FIG. 3 is a back view of the mower blade;

FIG. 4 is a right side view of the mower blade;

FIG. 5 is a left side view of the mower blade;

FIG. 6 is a top view of the mower blade; and,

FIG. 7 is a bottom view of the mower blade.

The broken lines depict portions of the mower blade in which the design is embodied that form no part of the claimed design.
